(57) **CLAIM**

The ornamental design for a connecting terminal, as shown and described.

DESCRIPTION

FIG. 1 is a bottom view of my new connecting terminal design;

FIG. 2 is a right side view of the connecting terminal design;

FIG. 3 is a front view of the connecting terminal design;

FIG. 4 is a left side view of the connecting terminal design;

FIG. 5 is a top view of the connecting terminal design;

FIG. 6 is an inverted rear view of the connecting terminal design; and,

FIG. 7 is a perspective front-right view of the connecting terminal design.

Broken lines in the figures are used to depict structure that is not part of the claimed design, but is considered necessary to show the environment in which the design is associated.
